EXHAUST PIPE FOR INTERNAL COMBUSTION ENGINES

Oscar Hansson, Goteborg, Sweden

Application March 12, 1936, Serial No. 68,554
In Sweden October 16, 1935

1 Claim. (Cl. 60—32)

This invention relates to internal combustion engines, blowers or the like and particularly to the exhaust pipes of such engines. The main object of this invention is an exhaust pipe which 5 does not cause such resistance against the escape of the exhaust gases that the power of the engine becomes reduced. A further object of the invention is an exhaust pipe of such a character that an expansion of the exhaust gases occurs 10 when flowing through said pipe, so that a vacuum is set forth therein which decreases the back pressure causing an increase of the net work done in the engine cylinder.

This invention is characterized mainly by the 15 feature that the exhaust pipe is shaped as a diffuser. Experience, however, has shown that the diffuser shape should not be arbitrary but that it should follow a distinct rule in which the velocity and the pressure of the gas flow at the intake end of the exhaust pipe as well as the 20 frequency of the exhaust impulses (the degree of discontinuity of the gas flow) are of considerable importance.

The rule of the shaping of the exhaust pipe 25 according to this invention is derived from the two well known formulae of Euler, from which the following formula has been derived, viz:

$$s = \frac{1}{s_0} \cdot \frac{1}{L} \left(\frac{1}{s_0} - \frac{1}{s_{\max}} \right) x$$

In this formula s is the variable cross section 30 at the distance x inches from the smallest cross section s_0 , in square inches while $s_{\max}$ is the 35 largest cross section and L is the length in inches of the diffuser measured between the cross sections s_0 and $s_{\max}$.

The sections s_0 and $s_{\max}$ are to be determined 40 in each case according to the existing circumstances, that is, according to the gas volume passing through the pipe as well as to such velocities of the flow which are convenient with regard to the resistances in the pipe.

Experience has shown that a suitable relation 45 between the various dimensions will be obtained if:

$$s_0 = A \cdot V \cdot n, s_{\max} = B, s_0, \text{ and } L = C \left(\frac{1}{n} - D \cdot V \cdot \frac{\phi}{ns_0} \right)$$

In these formulae A , B , C and D are constants

depending on the value of the piston speed, valve opening, number of cylinders and firing order of the respective motor. V is the cylinder volume in cubic inches, n is the number of revolutions per minute, s_v is the maximum opening of the 5 exhaust valve in square inches and ϕ is the number of degrees for the crank shaft from the moment when the exhaust valve commences to lift until it has reached its full lift.

It is not necessary that the exhaust pipe in 10 its entire length has the configuration of a diffuser, but it can begin as well as end in a plain cylindrical tube according to the local circumstances. Further, this diffuser may be positioned more close to or farther away from the exhaust 15 valves of the exhaust manifold in a multi-cylinder engine.

In the accompanying drawing an embodiment 20 of this invention is illustrated by way of example, wherein

Figure 1 is a sectional elevation view of the 25 exhaust diffuser, and

Figures 2 and 3 cross-sections on the lines 30 II—II and III—III respectively of Figure 1.

In the drawing, s_0 designates the smallest 25 cross-section, $s_{\max}$ the largest cross section, and L the total length of the diffuser, while the sections shown in Figures 2 and 3 can be designed 35 as of the sizes s_1 and s_2 respectively, which are at the respective distances x_1 and x_2 off the smallest section s_0 .

Having now particularly described and ascertained the nature of my said invention and in what manner the same is to be performed, I declare that what I claim is:—

A diffuser shaped vacuum-producing exhaust 40 pipe for internal combustion engines, blowers or the like characterized by the feature that the diffuser shape is determined by the following formula:

$$s = \frac{1}{s_0} \cdot \frac{1}{L} \left(\frac{1}{s_0} - \frac{1}{s_{\max}} \right) x$$

in which formula s is the variable cross section 45 at the distance x from the smallest cross section s_0 , while $s_{\max}$ is the largest cross section, and L is the length of the diffuser measured between the cross sections s_0 and $s_{\max}$.

OSCAR HANSSON.
